UNITED STATES PATENT OFFICE.

CLARENCE L. HARTWELL, OF CHICAGO HEIGHTS, ILLINOIS.

WOODWORKING-MACHINE.

No. 895,369.

Specification of Letters Patent.

Patented Aug. 4, 1908.

Application filed November 12, 1907. Serial No. 401,793.

To all whom it may concern:

Be it known that I, CLARENCE L. HARTWELL, a citizen of the United States, and a resident of Chicago Heights, in the county of Cook and State of Illinois, have invented a new and Improved Woodworking-Machine, of which the following is a full, clear, and exact description.

This invention contemplates an improved wood working machine for turning irregular or non-circular forms, the machine being more especially designed for shaping the eye portion of ax and other handles, although it is not limited to this particular operation as it may be used with advantage in the shaping of other articles, as will be apparent when the construction of the machine is fully understood.

Reference is to be had to the accompanying drawings forming a part of this specification, in which similar characters of reference indicate corresponding parts in all the views.

Figure 1 is a side elevation of the machine complete, with an ax handle in position preparatory to the shaping of the eye portion thereof; Fig. 2 is a plan of the machine; Fig. 3 is a right end elevation; Fig. 4 is a fragmentary cross-sectional view showing one position of the former; Fig. 5 is a similar section showing the former in a different position; Fig. 6 is a side elevation of the gripping-center, showing the bearing therefor in central vertical section; and Fig. 7 is a fragmentary sectional view through the sleeve and attached parts for controlling the movement of the machine carriage.

The machine embodies in its construction a suitable frame comprising supports 10, 10, carrying a table 11, the latter being provided with bearings 12 on its upper face, in which is journaled a spindle 13, having a driving pulley 14, keyed or otherwise secured thereto intermediate the bearings, and also having at the outside of one of said bearings near the forward end of the machine, a cutter-head 15, carrying a series of adjustable cutting blades 16.

At the front side of the machine frame is a carriage 17, arranged substantially the same height as the table 11, and secured to standards 18, which are rigid with a sleeve 19, slidably and revolvably mounted in bearings formed in the legs or supports 10 of the machine frame, and in an intermediate bearing 20 carried by a bar 21 disposed longitudinally of the machine frame and secured at

opposite ends to the supports 10. The bearing 20 carries a bracket or arm 22 which is provided with an overhanging forked end in which is fulcrumed a lever 23, the said lever 60 being also pivotally connected to the sleeve 19 and passing through a guide slot 24 formed on the carriage 17; this construction obviously operating when the lever 23 is shifted back and forth, to reciprocate the carriage and to move said carriage to and from the cutter-head when the lever is swung in a sidewise direction.

The standards 18 at the front end of the machine are extended above the carriage and 70 are provided with a longitudinally and horizontally-arranged bearing 25, and the rear standard 18 is likewise extended and provided with two alining bearings 26, and also an arm 27 rigidly connected therewith. Within 75 these bearings are carried the spindles or shafts of the gripping center 27^a and the tail center 28, the latter being in the nature of a cup for receiving the outer end of an ax handle or other piece of work to be shaped. The 80 gripping-center shaft is provided with a former 29, having a shape corresponding to that of the article to be fashioned, which, in the present instance, resembles the eye portion of an ax handle, and is adapted to bear 85 alternately against rests 30 and 31 which are secured to the machine table, the rest 30 being employed when shaping the pointed edge and flat sides of the handle, as illustrated in Fig. 5, and the rest 31 being used when shaping the enlarged or rounded portion of the handle, as shown in Fig. 4.

For revolving the work and the former 29 during the shaping process, the work-holding or gripping-center shaft is provided with a 95 crank 32. The work is gaged when placing it between the centers by a post 33, projecting upwardly from the carriage 17, and the carriage is limited in its swinging and longitudinal movement by a keeper 34, secured to 100 the machine frame around one of the standards 18, as best shown in Figs. 1 and 2. For moving the shaft of the tail center in gripping and releasing the work, the standard 18 at the forward end of the machine is provided with an arm or bracket 35, to which is fulcrumed a foot-lever 36 of bell-crank form, the said lever being also pivotally connected to a rod 37 passing through the sleeve 19. The opposite end of this rod is connected 110 with a lever 37^a fulcrumed intermediate its length on an arm 38 rigid with the rear

standard 18. The upper end of the lever 37^a is swivelly connected with a collar 39 adjustably secured to the shaft of the tail center by the set-screw shown, or other equivalent device.

The tail center is normally forced to a retracted position by a spring 40 secured to a fixed part of the machine and to the foot-lever 36. It is seen from this construction 10 that on depressing the foot-lever from its normal position, as shown in dotted outline in Fig. 1, to the position shown in full lines in said figure, the tail center will be advanced toward the work-holding center and will 15 press the work into engagement with the latter, whereby it is enforced to revolve by the revolution of the crank 32.

While I have shown and described the preferred manner of construction and arrangement of my improved machine, it will be apparent to those skilled in the art to which the invention appertains that various changes may be made, and I consider myself entitled to such modifications as fall within the scope 25 of the annexed claims.

Having thus described my invention, I claim as new and desire to secure by Letters Patent:

1. The combination of a frame, a spindle 30 revolvably mounted in bearings carried by the frame, a cutter-head carried by the spindle, a sleeve journaled in the frame having standards rigid therewith, bearings provided in the upper portions of the standards, carrying work-supporting centers, means for sliding one of the centers passing through the sleeve, and means for sliding and oscillating said sleeve.

2. The combination of a frame carrying a 40 revolvable cutter, a sleeve journaled in the frame having work-holding means at opposite ends for supporting the work adjacent to the cutter, means passing through the sleeve for varying the distance between the work-holding means, and means for sliding and oscillating said sleeve.

3. The combination of a frame carrying a 50 revolvable cutter, a sleeve journaled in the frame, having work-holding means for supporting the work adjacent to the cutter, a hand-lever for oscillating and sliding said sleeve, and means including a rod passing

through said sleeve, for advancing and retracting one of said centers.

4. The combination of a frame provided with a rotary cutter, a sleeve slidably and oscillatively mounted in the frame, having standards rigid therewith, centers carried by said standards, means for revolving one of said centers, and means for advancing and 55 retracting the other of said centers, including a rod passing through said sleeve.

5. The combination of a frame provided with a revoluble cutter, a carriage slidably and swingingly mounted at one side of said cutter, having centers for supporting the work, a hand-lever for swinging and sliding the carriage, and a foot-lever for advancing and retracting one of said centers.

6. The combination of a frame provided with cutting means, a sleeve journaled in the frame, having standards rigid therewith, centers carried by said standards for supporting the work adjacent to said cutting means, a foot-lever fulcrumed to one of said standards, 75 a rod connected with the foot-lever and passing through said sleeve, and a lever fulcrumed to the other of said standards and connected with said rod and to one of said centers.

7. The combination of a frame provided with a cutter, a carriage slidably and swingingly mounted at one side of said frame, having centers for supporting the work adjacent to said cutter, a hand lever for sliding and 85 swinging the carriage, and a foot lever operable to advance and retract one of said centers.

8. The combination of a frame provided with a cutter, a device revolvably and slidably mounted in the frame, having standards rigid therewith, centers carried by said standards, and a manually-operated lever connected at its end to said device and fulcrumed to a fixed part of the machine for 95 oscillating and reciprocating said device.

In testimony whereof I have signed my name to this specification in the presence of two subscribing witnesses.

CLARENCE L. HARTWELL.
